UNITED STATES PATENT OFFICE.

HORACE FALK NEUMEYER, OF MACUNGIE, PENNSYLVANIA.

FLASH-LIGHT LAMP.

No. 853,027.

Specification of Letters Patent.

Patented May 7, 1907.

Application filed September 12, 1906. Serial No. 334,302.

To all whom it may concern:

Be it known that I, HORACE FALK NEUMEYER, a citizen of the United States, residing at Macungie, in the county of Lehigh and State of Pennsylvania, have invented a new and useful Flash-Light Lamp, of which the following is a specification.

My invention relates to an improved flash-light apparatus, and has for one of its objects to provide an apparatus of this character which is simple and durable in construction, easy of operation and free from danger.

A further object of the invention is to provide an apparatus adapted for use in flash-light photography and capable of producing from magnesium or other suitable material, one or more flashes of light, of short or long duration, dependent upon the will of the operator.

20 A still further object of the invention is to provide an apparatus having separable parts, so that, when desired to carry the same in a valise, pocket or the like, it can be packed in a compact form; and also means for preventing the egress of the magnesium from the magazine when the apparatus is thus packed.

In the drawings:—Figure 1 is a top plan view of the complete apparatus. Fig. 2 is a 30 vertical sectional view, taken on the line 2—2 of Fig. 1, and showing the apparatus ready for operation. Fig. 3 is a vertical sectional view of the magazine, showing the caps thereof in position for preventing the egress of its 35 contents. Fig. 4 is a front elevation of the upper cap showing the arcuate slot. Fig. 5 is an end view of the cylinder taken on the line 5—5 of Fig. 3. Fig. 6 is a front elevation of the upper cap showing a modified 40 form of the discharge openings.

The same parts of the invention as shown in the drawings are designated by similar reference numerals.

Referring to the drawings, 1 designates 54 a preferably metallic open-ended cylinder which constitutes a receptacle or magazine for powdered magnesium or other suitable inflammable material. Located in the lower end of the magazine is an air-tube 2, having 50 one end 3 of its horizontal portion 4 fitted upon a stud 5 extending inwardly from the wall of the magazine. The other end of the horizontal portion extends through the wall of the magazine at a point directly opposite 55 the stud 5 and terminates in a nipple 6 for the attachment of a flexible air-tube 7

through which air under pressure is led to the air tube 2. The air-tube 2 also comprises a vertical portion 8 having threaded connection at its upper end 9 with the horizontal portion 4 of said tube. This vertical portion 8 of the air-tube is coaxial with the magazine and the lower or discharge end 10 is extended beyond the lower end 11 of the cylinder.

The lower end of the cylinder is closed by a screw-cap 12, preferably having an integral external knob 13 to facilitate the adjustment thereof. The upper or inner surface of the cap 12 is provided with an axial concavity or depression 14 adapted to receive the discharge 65 end of the air-tube in one position of the cap.

The upper end of the cylinder is closed by a second screw-cap 15 having an arcuate opening 16 located near the top of its annular wall; the walls of the opening being upwardly inclined in a manner to cause the powder to be projected in an upward direction. If desired, a series of openings 16^a 70 may be substituted for the arcuate opening or slot 16, as shown in Fig. 6 of the drawings. 80

Each of the caps 12 and 15 is provided with a knurled edge 17 to facilitate the turning of the cups and their consequent adjustment longitudinal of the cylinder.

Integral with the cylinder is a socketed 85 projection 18 located on the opposite side of the cylinder to the nipple 6 and at the other end of said cylinder. Extended into the socketed projection 18 is a stud 19 rigidly secured to, by means of the rivets 26, and supporting a pan 20. This pan is constructed of any suitable material and may be of any desired shape. Within the pan and secured to the bottom 21 thereof by means of rivets or other suitable devices 22, is an absorbent 90 pad 23, preferably asbestos or other non-combustible material. The upwardly and outwardly inclined sides 24 of the pan 20 are rigidly sustained in position by means of the reinforcing wire 25.

The operation of the apparatus is as follows: After assembling the various parts of the apparatus, and filling the magazine with powdered magnesium or other inflammable material, the lower screw-cap 12 of the magazine is adjusted to insure an air-gap between the discharge end 10 of the vertical portion of the air-tube 2, and the axial concavity or depression 14 located in the upper or inner surface of the cap. The second or upper 105 screw-cap 15 of the magazine is adjusted to a position that will uncover the passage 16,

thereby producing a means of egress for the contents of the magazine. The term "passage" includes a slot or a series of openings. After alcohol or other suitable inflammable liquid is poured upon the absorbent pad 23 in the pan 21, it is ignited by some suitable means, preferably a match. Air, under pressure is then applied to the free end of the flexible tube 7. The air is then forced through the flexible tube 7 and the air-tube 2. After passing from the discharge end 10 of the vertical portion 8 of the air tube 2, the air strikes the concavity or depression 14 and rebounds therefrom in a uniform manner throughout the magazine, thus forcing the contents therein through the arcuate opening 16 in an upward direction over the pan 21. The inflammable liquid in the pan 21 being inflamed, the powdered magnesium explodes as it comes in contact with said flame, and a flash of light is thereby produced. The density and length of this flash is dependent upon the amount and pressure of air sent into the magazine.

25 When desired to carry the apparatus in a valise, pocket or the like, the flexible tube 7 and the pan 21 are disengaged from the magazine. The two screw-caps 12 and 15 are tightly screwed on their respective ends 30 of the cylinder. In this position, the wall of the upper cap 15 closes the arcuate slot 16, and the concavity or depression 14 of the lower cap 12 closes the discharge end 10 of the vertical portion 8 of the air-tube 2. It 35 will, therefore, be seen that the ingress of air and the egress of the magnesium or other contents of the magazine, will be prevented.

Having thus described my invention, what I claim as new and desire to secure by Letters-Patent is:—

1. In a flash-light apparatus, the combination with a cylinder having an open end, of a cap adjustably mounted onto the said open end and having an arcuate discharge passage 45 formed in the side wall of the cap and communicating with the interior of the cylinder, and means for expelling the contents through the discharge passage, the said discharge passage being covered by the contiguous wall of the cylinder through the inward adjustment of the cap.

2. In a flash-light apparatus, the combination with a cylinder having an open end, of a cap adjustably mounted onto the said open end and having an upwardly inclined discharge passage formed in the side wall of the cap and communicating with the interior of the cylinder, and means for expelling the contents of the cylinder through the discharge 55 passage, the said discharge passage being covered by the contiguous wall of the cylinder through the inward adjustment of the cap.

3. In a flash-light apparatus, the combination with a cylinder having an open end, of a

cap adjustably mounted onto said open end and having a discharge passage formed in its side wall, a pan, means for attaching the pan to the cylinder below the discharge passage, the said discharge passage being covered by the contiguous wall of the cylinder through the inward adjustment of the cap.

4. In a flash-light apparatus, the combination of a magazine having a discharge orifice, of an air supply conduit mounted in the magazine, and a closure cap for the conduit adjustably mounted on the magazine to open and close the discharge end of the conduit.

5. In a flash-light apparatus, the combination with a magazine having a discharge passage, of an air supply conduit mounted in the magazine and provided with an internal discharge opening terminating beyond one end of the magazine, and a closure cap movably mounted on said end and adapted to open and close the discharge opening.

6. In a flash-light apparatus, the combination with a magazine having a discharge passage, of an air supply conduit mounted in the magazine and provided with an internal discharge opening contiguous to one end of the magazine, and a closure cap movably mounted on said end and adapted to open and close the discharge opening.

7. In a flash-light apparatus, the combination with a magazine having a discharge passage, of an air supply tube having a transverse portion and a vertical portion, the latter being open, and a cap movably mounted on one end of the magazine for closing the open end of the vertical portion of the tube.

8. In a flash-light apparatus, the combination with a magazine, of an interiorly arranged air supply conduit having its discharge opening facing outwardly, and a cap mounted on the magazine and provided with a concavity located in alinement with the discharge opening, said cap constituting means for closing said opening.

9. In a flash-light apparatus, the combination with a magazine having an opening at one end, of an air supply conduit having a projecting discharge tube extending toward the opening, and a cap mounted on the magazine for closing the opening and constituting means for closing the end of the discharge tube.

10. In a flash-light apparatus, the combination with a magazine having an open end, of an air supply conduit connected to the magazine, and a cap mounted on the open end of the magazine and constituting means for closing the air supply conduit.

11. In a magazine, an open-ended magazine provided at each end with a movable cap, a discharge passage located in one of the caps, an air conduit rigidly secured to and within the magazine, the other cap being located on the end of the magazine contiguous to the air conduit, said caps being respec-

tively adapted to prevent the egress of the contents of the magazine and the ingress of air into said magazine.

12. In a flash-light apparatus, an open-ended magazine having a closure cap mounted on each end thereof, an air-conduit rigidly mounted in the magazine, said conduit comprising a horizontal portion having one end fitted upon a stud integral with the wall of the magazine, and the other end passing through the wall at a point diametrically opposite the stud, and terminating in a nipple, and a downwardly extending discharge tube disposed in axial relation to the magazine and connected to the horizontal portion.

13. In a flash-light apparatus, an open-ended magazine having a closure cap mounted on each end thereof, an air-conduit rigidly mounted in the magazine, said conduit comprising a horizontal portion having one end fitted upon a stud integral with the wall of the magazine, and the other end passing through the wall at a point diametrically op-

posite the stud and terminating in a nipple, and a downwardly extending discharge tube 25 disposed in axial relation to the magazine and connected to the horizontal portion, and a cap threaded on the cylinder and having a recess to receive the lower end of the discharge tube.

14. In a magazine, an open-ended cylinder provided at each end with a movable cap, a discharge orifice located in one of the caps, a substantially T-shaped air-conduit rigidly secured to the wall of the magazine, and a 35 cap located on the other end of the magazine and having an axial concavity for receiving the discharge end of the air conduit.

In testimony, that I claim the foregoing as my own, I have hereto affixed my signature 40 in the presence of two witnesses.
